(57) CLAIM

The ornamental design for a display apparatus, as shown.

DESCRIPTION

FIG. 1 is a perspective view of the display apparatus showing our new design;

FIG. 2 is a front elevation view of the display apparatus shown in FIG. 1;

FIG. 3 is a right side elevation view of the display apparatus shown in FIG. 1, the left side elevation view being a mirror image thereof;

FIG. 4 is a rear elevation of the display apparatus shown in FIG. 1;

FIG. 5 is a top plan view of the display apparatus shown in FIG. 1; and,

FIG. 6 is a bottom plan view of the display apparatus shown in FIG. 1.

The surface(s) or portion(s) of the article not shown in the drawings or described in the specification form(s) no part of the claimed design.
